(57) **CLAIM**

We claim the ornamental design for a stand for pet feeding bowl, as shown and described.

DESCRIPTION

FIG. 1 is a perspective view of a stand for pet feeding bowl showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing a state of use thereof. The broken lines shown in FIG. 8 illustrate environmental structure. All other broken lines illustrate portions of the stand for pet feeding bowl. The broken lines form no part of the claimed design.
